SPARK PLUG CLEANING DEVICE
Louis M. Westerhouse, 2812 W. 20th St.,
Birmingham 8, Ala.
Filed May 1, 1961, Ser. No. 106,851
4 Claims. (Cl. 51—186)

This invention relates to a cleaning device onto which may be added an abrasive element and an abrasive substance, a combination that is especially adapted for the cleaning of spark plugs for internal combustion engines.

In the operation of an internal combustion engine, an accumulation of carbon and other foreign matter occurs that also in time accumulates within the cavity surrounding the insulator at the firing end of the spark plugs and which foreign matter will also accumulate on the said insulator itself, causing the spark plug to become short circuited and thereby preventing it from firing properly.

Many spark plug cleaners have been developed for cleaning out these deposits within the spark plug but these depend upon a permanent attachment to the cleaner itself which may become clogged and ineffective due to metal against the porcelain insulator not providing sufficient cleaning features to restore the insulator to its original appearance, especially where the spark plug cannot be dismantled for this cleaning.

This invention is illustrated in the accompanying drawings wherein

FIGURE 1 is a view of an elongated double ended cleaning device in which either end can be used as a cleaner, thus making it a two-in-one cleaner, with both cleaners being alike or they may vary for different size insulators;

FIG. 2 is an end view of a concavo-convex formation 19 shown at the top on line A—A FIG. 1 without the abrasive insert 23 and 24;

FIG. 3 is an end view of the formation 19 shown at the bottom on the line B—B FIG. 1 and shows the abrasive applied therein as 23 and 24;

FIG. 4 is a view on line C—C FIGS. 1, 7 and 8 showing a radius for the body of the device and a view 25 where the body thickness may be altered to provide a gauge for the spark gap. This alteration 25 is also shown in FIGS. 1, 7 and 8;

FIG. 5 is an enlarged view of the formation 19 constructed so as to fit into the cavity surrounding the insulator at the firing end and which formation contains an interchangeable stamping out of abrasive cloth as indicated by 23, with 24 being that part of 23 that hooks over a prong 22;

FIG. 6 shows two views of an interchangeable abrasive stamping 23 with the top view as it originally appears when stamped and with 24 being the place where it is to be buckled so as to be inserted over the prong 22 shown in FIGS. 1, 2, 5, 7, 8, 9 and 13. In the bottom enlarged view of this stamping it is shown with the part 24 buckled so it can be inserted over the prong 22 and with the sides 23 as they appear when inside the formation 19 in FIGS. 3, 5 and 13;

FIG. 7 is a view of the double cleaner as shown in FIG. 1 on line D—D and shows how the formation 19 straddles the ground electrode to the spark plugs 14 and 17 which are shown and where the insulator 16 is exposed by cutting away the threaded portions of the spark plugs at 15;

FIG. 8 is a folded single ended squeeze type cleaner arranged so the end of one leg of the cleaner forms a bearing on the outside of the spark plug 18 when the formation 19 is squeezed against the insulator 16 and which formation 19 may be modified as shown in FIG. 13;

FIG. 9 is a fragmentary view on line E—E of FIG. 8

2

which is that leg of the FIG. 8 device containing the formation 19.

FIG 10 is a diagram on line F—F FIG. 9 of a radius at the body of this device and which may vary as desired;

FIG. 11 is a fragmentary view on line G—G of the end of the outside leg of the squeeze type cleaner FIG. 8;

FIG. 12 is a view on line H—H FIG. 11 of the radius that may be used at the outside end and in the body of the cleaning device FIG. 8;

FIG. 13 is an enlarged view of the formation 19 as shown on line J—J FIG. 9 and is similar to that shown in FIG. 5 except that it shows a reduced distance for the sides of the formation 19 in the FIG. 8 device.

Having thus described the various figures in this invention it will be noted that 14 in FIG. 7 indicates an ordinary spark plug for internal combustion engines with the threaded portion cut away at 15 to expose the insulator 16 which is in the process of being cleaned by an oscillating movement of the cleaning device and with the abrasive element inserted within the formation 19 and with the hooked-over portion of the abrasive cloth shown at 24.

In FIGS. 1, 2, 3, 5, 7, 8, 9 and 13 various views of the formation 19 are shown. It will be noted they are tapered, being larger at the end to conform with the insulator and which taper is slightly reduced near the stem which supports the formation 19; however, the arc that is formed continues into the body of the device.

It will also be noted in the top cleaner formation FIG. 7 and in the FIG. 5, slots 20 are shown. These may be used to add some flexibility for the formation 19 when used over various sized insulators. The same is true with the slots 21 as shown in FIGS. 1, 2, 3, 5, 7, 8, 9

and 13; however, these slots 21 are necessary in order to provide a prong 22 onto which the abrasive element 23 may be hooked forming the hump 24 and through which slots 21 the abrasive cloth will pass so the abrasive sides 23 will come in contact with the insulator 16 and

in addition the slots are necessary to provide openings whereby an abrasive substance may be contained when this substance is used within the cavity surrounding the insulator 16 to assist in the cleaning of the cavity and the said insulator.

In FIGURES 1, 4, 7 and 8, a gauge 25 is shown in the body of the device that may be used to check the opening in the spark gap.

To accomplish the process of thoroughly cleaning the spark plug cavities and insulators as referred to, the cleaning formation 19 may be first inserted within the cavity surrounding the insulator 16 to clean it out as much as possible with the possible inclusion of an abrasive substance during the oscillating movements of the cleaning device within the said cavity. To thoroughly clean the said insulator usually requires more attention and this cleaning can be accomplished by oscillating the abrasive insert 23 in a combination with the cleaning formation 19 within the cavity surrounding the insulator 16 and if this does not restore the said insulator to its original appearance it can be further polished by dampening the abrasive element and/or an abrasive substance with a liquid thereby using this liquid in combination with the other features used in the cleaning process.

Having thus described my invention I claim:

1. A spark plug cleaning device provided with a transversely curved concavo-convex formation constructed so as to enter the cavity surrounding the insulator at the firing end of a spark plug, with said formation having a taper to conform with that of the said insulator and supported at the center by a stem having an arc which continues from the said formation and with said concavo-convex formation having sides that will extend under the

ground electrode of the said spark plug when the said transversely curved concavo-convex formation is oscillated within the said cavity.

2. A spark plug cleaning device provided with a circular cleaning portion, with its sides extended so as to go under the ground electrode of the spark plug, when the said circular portion is oscillated within the cavity surrounding the insulator at the firing end of the said spark plug and with the said circular cleaning portion supported at the center by a stem that is provided with an arc that continues into the body of the cleaning device and having a number of longitudinal slots extending up from the end between two of which there is a prong over which an interchangeable abrasive element may be hooked with the sides of the said abrasive element passing through two of the slots from which the said sides of the abrasive element extend around on the inside of the said circular cleaning portion, with the abrasive side of the said abrasive element turned to polish the said insulator.

3. An elongated double ended spark plug cleaning device having an arc throughout its entire length with each end provided with a transversely curved concavo-convex formation, that is supported by a stem at its center and having sides constructed so they will pass under the ground electrode to the said spark plug when the said formation is oscillated within the cavity which surrounds the insulator at the firing end of the said spark plug and with said transversely curved concavo-convex formation provided with a number of longitudinal slots extending from the ends which may be used to contain an abrasive

substance and between two of which to provide a prong over which an abrasive element may be hooked and with the sides of the said abrasive element passing through two of the said slots from which the said sides of the cleaning elements extend around on the inside of the said transversely curved concavo-convex formation with the abrasive sides of the said abrasive elements turned to polish the said insulator of the spark plug.

4. A folded squeeze inverted U-type spark plug cleaner having an arc throughout its length and having the end of an outside leg that may be squeezed against the outside surface of the spark plug while the end of the opposite leg which contains a transversely curved concavo-convex formation is pressed against the sides of the insulator within the cavity of the spark plug at the firing end. Said transversely curved concavo-convex formation is provided with a number of slots extending longitudinally from the end between two of which there is a prong over which an abrasive element may be hooked with the sides of the said abrasive element passing through these said slots and from which slots the sides of the said abrasive element extend around on the inside of the said transversely curved concavo-convex formation with the abrasive side of the said abrasive element turned so as to polish the said insulator as the two legs of this device are squeezed toward each other and the said abrasive element is pressed against the said insulator as it is oscillated within the said cavity.
